UNITED STATES PATENT OFFICE.

FRANCESCO PUCILLO, OF LONDON, ENGLAND.

STRUCTURE OR FRAMES FOR BUILDINGS OR THE LIKE.

1,194,320.

Specification of Letters Patent. Patented Aug. 3, 1913.

Application filed February 23, 1912. Serial No. 79,915.

To all whom it may concern:

Be it known that I, FRANCESCO PUCILLO, a subject of the King of Italy, and residing at 46 Grosvenor Road, London, S. W., England, have invented certain new and useful 5 Improvements in Structures or Frames for Buildings or the like, of which the following is a specification.

This invention relates to improvements in 10 structures or frames for buildings or the like and has for its object to devise an improved construction which shall be particularly applicable in the case of portable buildings in which ease and rapidity of assembling and 15 dismantling is a great desideratum, the invention also being useful for other purposes.

In the construction of all known forms of 20 portable buildings made of wood or metal sections the various elements or sections are joined to one another by means of any of 25 the various known mechanical joints such as nails, bolts and nuts, screws and the like, which in addition to constituting a source of weakness in the structure are such that 30 their surfaces are subject to deterioration and they thus militate against a rapid dismantling or taking apart of the elements forming the structure. Furthermore, in all 35 such structures the various elements whether of wood or metal had a definite geometrical form which did not allow of the parts being interchangeable as they were designed for the stresses which the member might be called upon to bear and thus it was impossible to use any given weight of material 40 to the best advantage when providing structures of differing forms or sizes.

By means of this invention the above disadvantages are entirely obviated and, in addition, structures may be produced which 45 are compact and rigid and at the same time extremely light, having regard to the amount of resistance to stress which each element in the structure is capable of offering.

According to this invention an extremely 50 strong, rigid and light structure of framing is formed mainly of a series of elements or members of uniform section from a material, such as sheet steel, for example, which 55 material is deformable, the said elements being connected together by a male portion or spigot on one element and a corresponding female portion or socket on the other element, the two portions forming the joint or 60 coupling being adapted to slide relatively to 65 each other without any relative rotary move-

ment, preferably, in such a manner as to cause the inner and outer surfaces of all the framing to lie in the same planes respectively, thereby facilitating covering the structure with outer coverings or both outer coverings and linings consisting of sheets or slabs of asbestos board or wooden boards or other suitable material or materials. The elements for forming the framework are 65 suitably of channel section, but they may be of hollow oblong or square or curvilinear or polygonal section. One kind of element is, for example, provided with a male joint or coupling part of straight or hook-shape 70 formed by cutting and also in some cases by bending and the other kind of element is also formed by cutting and in most cases also by bending in such a manner as to allow of being engaged by the said male device. 75

The portions of the elements to be connected are so constructed as to slide relatively to one another but have no relative rotational movement, while the locking of the members together is performed by bending either the male portion of one member or an adjacent part or parts of the other member forming the joint. 80

The invention also consists in other details and arrangements hereinafter more 85 particularly referred to.

In the accompanying drawings which illustrate by way of example one convenient mode of carrying out the invention:—Figure 1 is a fragmentary view in elevation 90 showing a portion of a structure formed in accordance with the invention; Fig. 1^a is a perspective view of a detail; Fig. 2 is a sectional elevation upon the line A—B of Fig. 1; Fig. 3 is a sectional elevation upon the 95 line C—D of Fig. 1; Fig. 4 is a sectional plan upon the line E—F of Fig. 1; Figs. 5 and 6 are sectional plans upon the lines G—H and I—K respectively. Fig. 7 is a perspective view of the joint shown in Fig. 100 5; showing one member being slid into position.

In carrying this invention into effect in one convenient manner when constructing, for example, a portable hut or like building, 105 the framework of the building is formed as a whole or in various sections which may be subsequently joined together in any suitable manner and however the framework be constituted the elements or members employed 110 in its construction are formed from a readily bendable material such as, for example,

sheet steel, the elements being formed by bending the sheets into channel, tubular, part-tubular or other suitable form of such shape and dimensions in cross-section as to 5 enables the element to withstand the stresses to which it will be subject, having regard to its position in the structure and the function which it is called upon to perform. In practice it is convenient, having decided 10 upon the form of the elements of any particular structure, to retain a uniform formation of such elements throughout the structure, but it will of course be understood that any suitable form may be chosen for any 15 particular building, having regard to the nature and size of such building.

In the example illustrated the framework or each section thereof, is formed from a number of sheet metal elements, mostly of 20 uniform channel section, and comprising simple uprights or verticals *a* and double or compound uprights *b* disposed alternately, the double verticals being formed by the juxtaposition back to back of two simple 25 members connected together by blocks or distance pieces *c* welded or soldered or otherwise affixed to the elements.

In addition the framework comprises upper and lower beams or girders marked *d* 30 and *e* respectively and intermediate or transverse rails or ties *f*, simple floor beams *g*, double or compound floor beams *h* and architrave or roof truss *i*.

In connecting the upper members *d* to the 35 vertical members or posts *a* and *b* the latter may be provided with tongues *k* adapted to be passed through slots in the web of the upper member and, if desired, the tongues *k* may be folded down thereon in the manner 40 clearly shown in Fig. 1, the downwardly depending flange *l* (Figs. 2 and 3) of the upper member *d* being conveniently adapted to rest in recesses formed by cutting away the upper portion of the inner flange of each 45 of the vertical members. The outer and up-standing flange of the upper member *d* is flush with the outer flanges of the vertical members so that substantially flush inner and outer faces will be presented for the 50 reception of the water-proof or other sheeting or covering that may form the inner walls or outer walls or both inner and outer walls of the completed building. The blocks or distance pieces *c* in addition to forming 55 locking members for the various elements of the structure also afford ready means for the attachment of the wall-covering sheets or slabs both inside and outside.

The connection between the members *f* 60 and the elements *a* *b* is effected by partly cutting the flanges on the line I—K and bending the portions below the cut inward as shown at *m* and in cutting the flanges of the member *f*, see Figs. 1 and 1^a, as at *n* and 65 bending them at *f' f'* in order to assume

such a formation as to be adapted to engage in the space formed between the two flanges of the members *a* or *b*. Consequently the male portions or prongs *f'* are of slightly smaller dimensions or width, externally, so 70 as to permit of being inserted, and of fitting exactly, into the space between the inwardly bent flanges of the member *a* or *b*. Moreover, it should be understood that, in order to allow the adjacent portions *f'' f''* of the 75 flanges of the element *f* to enter between the undeformed portions of the flanges of the elements *a* and *b*, the flanges of the latter may be slightly sprung apart or splayed while the connection between the elements is 80 being effected as shown in Fig. 7.

If the ends of the flanges of the members *a* or *b* adjoining the top or web of the member *f* be slightly closed in or brought together beyond their normal position so that 85 they will be just above the piece *f*, the latter can no longer move back in the vertical direction and the joint is locked with the maximum of simplicity and strength.

Another form of simple joint or coupling 90 is shown most clearly in Figs. 1 and 2 and consists in the connection of a vertical double member *b* with its corresponding lower horizontal member *h*.

The web of each component of the member *b* terminates in a tongue or extension *o* (Figs. 1 and 2) each of which is bent as shown at *o'* and is slotted at *o''*, the slot being adapted, by sliding horizontally, to engage a block or distance piece *c'* welded between the elements that constitute the member *h*. Each of the flanges of the member *b* terminates in a bent portion *p* which completes the joint as follows:—The flanges of the member *h* are cut as shown at *q*, the cut portion being slightly raised and arranged to abut against the flanges *p*. Consequently, the tongue *o* that is held down by the block *c'* will be prevented from sliding horizontally and therefore the joint is rigid 100 and at the same time simple and easy to take apart by returning the cut portions *q* to their normal positions.

Another simple joint or coupling is shown 105 in Figs. 1 and 2, connecting the roof trusses to the uprights or posts *b* of the walls. The roof truss *i* has bent plates *r* terminating in the extensions or straps *r'* which fit exactly into an opening formed in the web of the piece *d* already secured to the member *b*. The transverse pin or locking member *s* engaging beneath the distance pieces *c* that are welded between the two elements of the piece *b* completes the joint, when the end of each of the tongues *r'* has been bent around 110 one side of a pin *s*, suitably passed between the webs of the member *b* and taking a bearing against the blocks *c*.

The connection between the simple members *a* and their corresponding members 115

or floor joists *g* is effected by means of a simple male and female joint or coupling as indicated in Fig. 3, and comprising a tongue *t* passing through loops *u* in the web formed by slotting and pressing into shape and locked by bending the lower end over the flange of the member *g*. A similar connection is made, in some cases between the rails or horizontal members *f* and the backs of the uprights or vertical members *a* where a tongue *v* enters the loop *w* formed by slotting and bending the web of the element *a* and is locked by bending at *v* (Fig. 1).

The joint first indicated as being of a male and female type and shown as employed for connecting the pieces *f* to the pieces *b*, is repeated for connecting the floor joists or pieces *h* to the pieces *e* (Figs. 1 and 4), and also here the deformability of the material allows of locking the joint or coupling the joint between the members.

By the combination of the joints described the simple joint or coupling between the different members is always or may be completed by a small deformation of the material which allows of locking the joint so that it cannot come apart until the deformable locking portions have been returned to their normal position. The rigid members *d* and *e* are consequently rigidly connected together and the members *f* whose ends abut against the members *a* consequently form additional connections.

The manner of jointing or coupling, the locking of the joints, and the arrangement of the members, while capable of wide variation within the scope of the invention, allow of producing a construction having a maximum strength and rigidity and which, nevertheless, can be easily erected and taken down or dismantled.

Having now described my invention, what I claim as new and desire to secure by Letters Patent is:—

- 45 1. In a frame-work structure for buildings and the like, members formed from easily bendable material of uniform section and being of channel shape in cross-section, and means for connecting pairs of said members when the end of one is inserted in the other comprising a projecting part on one of the members and a slotted portion on the other member adapted to fit over the projecting part so as to form a sliding connection, and a bent portion on one of said members engaging a portion of the other so as to prevent disengagement of such members when the sliding member is in position.
- 50 2. In a frame-work structure for buildings and the like, members formed from easily bendable material of uniform section and being of channel shape in cross-section, and means for connecting pairs of said members when the end of one is inserted in the other comprising a projecting part on one of the members and a slotted portion on the other member adapted to fit over the projecting part so as to form a sliding connection, and a bent portion on one of said members engaging a portion of the other so as to prevent disengagement of such members when the sliding member is in position, and means for rigidly connecting certain of the members so as to form compound members.
- 55 3. In a frame-work structure for buildings and the like, the combination of upright members of channel cross-section and made of easily bendable material, horizontal members of the same in cross-section having slotted portions near the ends thereof, means for connecting the ends of the horizontal members to the upright members comprising inturned portions of the flanges of the upright members adapted to be slidably engaged by said slotted portions, and means for rigidly retaining the latter when slid into position comprising inwardly bent portions of the flanges of the upright members.
- 60 4. In a frame-work structure for buildings and the like, the combination of an upright member composed of two parts of easily bendable material of channel section arranged back to back and rigidly connected by distance pieces, horizontal members of the same cross section as each part of the upright member and having slotted portions near the ends thereof, means for connecting the ends of said horizontal members to the upright member comprising inturned portions of the flanges of each of the channeled parts of the upright member adapted to be slidably engaged by said slotted portions, the ends of the horizontal members being pressed inward so as to fit between the flanges of the upright member, and means for rigidly, but separably, retaining the horizontal members in position comprising slightly inwardly bent portions of the flanges of the upright member.
- 65 5. In a frame-work structure for buildings and the like, the combination of an upright member composed of two parts of easily bendable material of channel section arranged back to back and rigidly connected by distance pieces, horizontal members of the same cross section as each part of the upright member and having slotted portions near the ends thereof, means for connecting the ends of said horizontal members to the upright member comprising inturned portions of the flanges of each of the channeled parts of the upright member adapted to be slidably engaged by said slotted portions, the ends of the horizontal members being pressed inward so as to fit between the flanges of the upright member, and means for rigidly, but separably, retaining the horizontal members in position comprising slightly inwardly bent portions of the flanges of the upright member.
- 70 6. In a frame-work structure for buildings and the like, the combination of an upright member composed of two parts of easily bendable material of channel section arranged back to back and rigidly connected by distance pieces, horizontal members of the same cross section as each part of the upright member and having slotted portions near the ends thereof, means for connecting the ends of said horizontal members to the upright member comprising inturned portions of the flanges of each of the channeled parts of the upright member adapted to be slidably engaged by said slotted portions, the ends of the horizontal members being pressed inward so as to fit between the flanges of the upright member, and means for rigidly, but separably, retaining the horizontal members in position comprising slightly inwardly bent portions of the flanges of the upright member.
- 75 7. In a frame-work structure for buildings and the like, the combination of an upright member composed of two parts of easily bendable material of channel section arranged back to back and rigidly connected by distance pieces, horizontal members of the same cross section as each part of the upright member and having slotted portions near the ends thereof, means for connecting the ends of said horizontal members to the upright member comprising inturned portions of the flanges of each of the channeled parts of the upright member adapted to be slidably engaged by said slotted portions, the ends of the horizontal members being pressed inward so as to fit between the flanges of the upright member, and means for rigidly, but separably, retaining the horizontal members in position comprising slightly inwardly bent portions of the flanges of the upright member.
- 80 8. In a frame-work structure for buildings and the like, the combination of an upright member composed of two parts of easily bendable material of channel section arranged back to back and rigidly connected by distance pieces, horizontal members of the same cross section as each part of the upright member and having slotted portions near the ends thereof, means for connecting the ends of said horizontal members to the upright member comprising inturned portions of the flanges of each of the channeled parts of the upright member adapted to be slidably engaged by said slotted portions, the ends of the horizontal members being pressed inward so as to fit between the flanges of the upright member, and means for rigidly, but separably, retaining the horizontal members in position comprising slightly inwardly bent portions of the flanges of the upright member.
- 85 9. In a frame-work structure for buildings and the like, the combination of an upright member composed of two parts of easily bendable material of channel section arranged back to back and rigidly connected by distance pieces, horizontal members of the same cross section as each part of the upright member and having slotted portions near the ends thereof, means for connecting the ends of said horizontal members to the upright member comprising inturned portions of the flanges of each of the channeled parts of the upright member adapted to be slidably engaged by said slotted portions, the ends of the horizontal members being pressed inward so as to fit between the flanges of the upright member, and means for rigidly, but separably, retaining the horizontal members in position comprising slightly inwardly bent portions of the flanges of the upright member.
- 90 10. In a frame-work structure for buildings and the like, the combination of an upright member composed of two parts of easily bendable material of channel section arranged back to back and rigidly connected by distance pieces, horizontal members of the same cross section as each part of the upright member and having slotted portions near the ends thereof, means for connecting the ends of said horizontal members to the upright member comprising inturned portions of the flanges of each of the channeled parts of the upright member adapted to be slidably engaged by said slotted portions, the ends of the horizontal members being pressed inward so as to fit between the flanges of the upright member, and means for rigidly, but separably, retaining the horizontal members in position comprising slightly inwardly bent portions of the flanges of the upright member.
- 95 11. In a frame-work structure for buildings and the like, the combination of an upright member composed of two parts of easily bendable material of channel section arranged back to back and rigidly connected by distance pieces, horizontal members of the same cross section as each part of the upright member and having slotted portions near the ends thereof, means for connecting the ends of said horizontal members to the upright member comprising inturned portions of the flanges of each of the channeled parts of the upright member adapted to be slidably engaged by said slotted portions, the ends of the horizontal members being pressed inward so as to fit between the flanges of the upright member, and means for rigidly, but separably, retaining the horizontal members in position comprising slightly inwardly bent portions of the flanges of the upright member.
- 100 12. In a frame-work structure for buildings and the like, the combination of an upright member composed of two parts of easily bendable material of channel section arranged back to back and rigidly connected by distance pieces, horizontal members of the same cross section as each part of the upright member and having slotted portions near the ends thereof, means for connecting the ends of said horizontal members to the upright member comprising inturned portions of the flanges of each of the channeled parts of the upright member adapted to be slidably engaged by said slotted portions, the ends of the horizontal members being pressed inward so as to fit between the flanges of the upright member, and means for rigidly, but separably, retaining the horizontal members in position comprising slightly inwardly bent portions of the flanges of the upright member.
- 105 13. In a frame-work structure for buildings and the like, the combination of an upright member composed of two parts of easily bendable material of channel section arranged back to back and rigidly connected by distance pieces, horizontal members of the same cross section as each part of the upright member and having slotted portions near the ends thereof, means for connecting the ends of said horizontal members to the upright member comprising inturned portions of the flanges of each of the channeled parts of the upright member adapted to be slidably engaged by said slotted portions, the ends of the horizontal members being pressed inward so as to fit between the flanges of the upright member, and means for rigidly, but separably, retaining the horizontal members in position comprising slightly inwardly bent portions of the flanges of the upright member.
- 110 14. In a frame-work structure for buildings and the like, the combination of an upright member composed of two parts of easily bendable material of channel section arranged back to back and rigidly connected by distance pieces, horizontal members of the same cross section as each part of the upright member and having slotted portions near the ends thereof, means for connecting the ends of said horizontal members to the upright member comprising inturned portions of the flanges of each of the channeled parts of the upright member adapted to be slidably engaged by said slotted portions, the ends of the horizontal members being pressed inward so as to fit between the flanges of the upright member, and means for rigidly, but separably, retaining the horizontal members in position comprising slightly inwardly bent portions of the flanges of the upright member.

In testimony whereof I have signed my name to this specification.

FRANCESCO PUCILLO.
